UNITED STATES PATENT OFFICE.

JOSEPH F. SWAB, OF CEDAR RAPIDS, IOWA.

SHIPPING MILK-CAN.

SPECIFICATION forming part of Letters Patent No. 293,682, dated February 19, 1884.

Application filed December 6, 1883. (No model.)

To all whom it may concern:

Be it known that I, JOSEPH F. SWAB, a citizen of the United States, residing at Cedar Rapids, in the county of Linn and State of Iowa, have invented certain new and useful Improvements in Shipping Milk-Cans, of which the following is a specification, reference being had therein to the accompanying drawings, in which—

10 Figure 1 is a central vertical section of the can and float. Fig. 2 is a perspective view of the can. Fig. 3 is a perspective view of the float, and Fig. 4 a vertical section of the same.

15 My invention relates to improvements in cans and floats used in the transportation of milk, and is related to the devices shown in the United States Patent No. 282,585, granted to me August 7, 1883; and the object of my improvements is to provide a more durable, 20 convenient, and efficient device for accomplishing the results contemplated.

25 The invention consists in the construction and arrangement of the several parts herein-after described, and specifically pointed out in the claims.

The can is composed of an inner cylindrical vessel, A, of sheet metal, having its upper edge flanged outwardly, and soldered to the upper flange and surface of the upper hoop, B, of 30 the casing C. This casing is generally of octagonal shape, and made of wood, and a packing of suitable non-conducting material, D, is interposed between the can and casing. Within the lower end of the casing is placed the 35 wooden bottom E, having an octagonal periphery or corresponding with the form of the casing.

To retain together the lower end of the staves forming the casing, and also the bottom 40 E, a polygonal band or hoop, F, of heavy tin or sheet metal, is used to surround said staves. The lower half or third of the hoop F is slit 45 at the angles corresponding with the joints of the staves, and the segments F' thus produced are flanged inwardly, and the two adjoining edges produced by the slits above stated are made to overtop each other, as shown at f, to produce a double thickness of sheet metal at these points, projecting beyond 50 the flange of the adjoining segments and protecting it against abrasion when the cans are

dragged upon the ground. The two thicknesses of sheet metal are soldered together at f, and the wood bottom E and flanged segments F' are thus retained securely until the 55 metal is worn out. If desired, nails or screws f² may be driven through the hoop F into the staves and the bottom of the casing as additional security. The upper hoop, B, is formed in an inverse manner—that is, with a smooth 60 and level top—but the segmental sides are reinforced at the angles of the casing. For this purpose an annular disk of sheet metal is used, in the outer periphery of which a slit is made to correspond with each angle of the casing, 65 and after having folded each segment so as to rest against one of the staves, one of the edges of the slits is bent laterally, and the triangular piece b thus obtained is bent under the adjoining edge of the slit and soldered thereto, 70 forming a strong connection between the segments at that point. The inner edge of the disk is bent upward at b², to support the flanged edge a of the inner vessel, A. The cover G, to close the latter, has a cylindrical portion, 75 g, that fits within the mouth of the vessel A, and also a bottom disk, g', and an upper disk, g². The latter, extending beyond the cylindrical portion g, rests upon the flanged edge of the inner vessel. An air-chamber, 80 G', is thus formed within the cover, to render the contents of the vessel less subject to changes of the temperature. The cover is also provided with a central opening, g³, to either ventilate the interior of the vessel or receive milk 85 from a suitable funnel. At other times the opening g³ is closed by a small cover, G², pivoted upon a bolt, g⁴, passing through both disks of the cover and through a small block of wood, g⁵, fitting between the disks in their central 90 portion, to prevent said disks from being so compressed together by the nut upon the bolt g⁴ as to become strained and deformed. The cover is provided with handles g⁶, to facilitate its removal from the can when desired. 95

Within the vessel A is placed the float H. It is made of sheet metal, and has an outer cylinder, h, of such diameter as to nearly fit the interior of the can in which the float is to be used. 100

Within the cylinder h, and concentric therewith, is a second cylinder, h', the diameter and

height of which is about half as large as the cylinder h . The upper edges of these cylinders are united by an annular flaring cover, h^2 , soldered thereto, so as to produce air-tight joints with the upper edges of both cylinders and form of its upper surface a conical funnel, to direct milk poured upon it from the circumference toward the central opening, and the latter opening is provided with a cover, k , preferably cone-shaped, with its apex uppermost, and said cover is secured to the inner edge of the flaring funnel h^2 . The central cover, k , is constructed of fine wire-gauze or of perforated sheet metal, to allow milk to pass downward therethrough and air upward through the center of the float, and at the same time prevent flies and foreign substances from entering or falling in the milk contained in the can. Handles m are secured to the top of the cover h^2 of the float, to facilitate its being lifted from the can. By this construction of the float an air-chamber, H' , is produced under the cover h^2 , between the two concentric cylinders, that gives to the whole a light specific gravity, and causes the device to float upon the milk and prevent its splashing, agitation, and churning often produced while under transportation. The air-chamber H' can have its lower portion open, as shown in Fig. 1, or closed, as shown in Fig. 4, the effect being substantially the same.

By having the central cover, k , perforated, as above stated, the float need not be removed from the can before filling the latter, as the milk can be poured upon the float, and, although temporarily submerging the latter, it will pass through the perforations of the cover k and descend under the float, and consequently no care need be exercised or attempt be made to pour the milk in the center only, as the flaring funnel h^2 extends from the periphery of the can and directs the whole volume of milk toward the central screened opening.

Having now fully described my invention, I claim—

1. In combination with the polygonal wood casing of a milk-can, the upper hoop, B , of sheet metal, having a smooth uninterrupted horizontal surface, and sides composed of plane segments, having one of their ends overlapping the flanged end b of the adjoining segment, and soldered thereto, substantially as and for the purpose described. 45

2. The combination, with the polygonal wood casing and bottom of a milk-can, of the lower hoop, F , of sheet metal, having its upper portion formed with angles corresponding with the wood casing, and its lower portion slitted and bent under the bottom of the casing, and one end of each turned-under segment overlapping the end f of the adjoining segment, substantially as and for the purpose described. 55

3. In a transportation milk-can, a float composed of two concentric cylinders, the inner one of less depth than the outer one, an air-tight cover extending from the top edge of the outside cylinder inward and downward to the top edge of the inner cylinder, and a perforated cover secured over the central opening of the inner cylinder, substantially as and 65 for the purpose set forth. 70

4. The combination of the concentric cylinders $h h'$, of different length, the flat annular disk uniting them at the bottom, the flaring annular cover uniting the upper edges of said cylinders, and the perforated cone d over the inner cylinder, whereby a milk-can float is produced, to operate as set forth, for the purpose specified. 75

In testimony whereof I affix my signature in 80 presence of two witnesses.

JOSEPH F. SWAB.
